UNITED STATES PATENT OFFICE.

ZERO W. WEBB, OF MOUND CITY, ILLINOIS.

DESIGN FOR A PRINTING DEVICE FOR PHOTOGRAPHERS.

53,213.

Specification for Design.

Patented Apr. 15, 1919.

Application filed July 14, 1916. Serial No. 109,395. Term of patent 14 years.

To all whom it may concern:

Be it known that I, ZERO W. WEBB, a citizen of the United States, residing at Mound City, in the county of Pulaski and State of Illinois, have invented a new, original, and ornamental Design for Printing Devices for Photographers, of which the following is a specification, reference being had to the accompanying drawing, forming part thereof.

The figure is a perspective view of a

printing device for photographers, showing my new design.

I claim:

The ornamental design for a printing device for photographers, as shown.

ZERO W. WEBB.

Witnesses:

GEO. A. THARP,
CHAS. L. RICE.
